Filed Apr. 5, 1963, Ser. No. 74,311

Term of patent 14 years

(Cl. D52—6)

FIG. 1.

FIG. 2.

FIG. 3

FIG. 1 is a front elevational view of an atmospheric condition indicating instrument dial, showing our new design.

FIG. 2 is a perspective view thereof shown encased in a housing disclosed in broken lines for illustrative purposes only.

FIG. 3 is a side view of FIG. 2 showing in section the dial portion.

In FIGURE 2, the said dial structure is depicted in a typical setting indicated by the broken-line form surrounding said dial portion.

We claim:

The ornamental design for an atmospheric condition indicating instrument dial, as shown and described.
